UNITED STATES PATENT OFFICE.

JOHN KIEWICZ, OF HYDE PARK, AND CHRISTIAN H. T. HAGELSTEIN, OF DORCHESTER, MASSACHUSETTS, ASSIGNORS TO THE REECE BUTTON HOLE MACHINE COMPANY, OF BOSTON, MASSACHUSETTS, A CORPORATION OF MAINE.

BUTTON-ATTACHING MACHINE.

1,181,228.

Specification of Letters Patent.

Patented May 2, 1916.

Application filed February 17, 1914. Serial No. 819,160.

To all whom it may concern:

Be it known that we, JOHN KIEWICZ and CHRISTIAN H. T. HAGELSTEIN, citizens of the United States, residing at Hyde Park, 5 in Norfolk county, and at Dorchester, in the county of Suffolk, respectively, and State of Massachusetts, have invented certain new and useful Improvements in Button-Attaching Machines, of which the following is a specification, reference being had therein to the accompanying drawing.

This invention relates to button attaching machines, and more particularly to machines for attaching a series of shank-eye 15 buttons by thread or the like to a piece of work such as a shoe or other garment.

For convenience the present invention is illustrated as applied to the same general type of button attaching machine which has 20 heretofore been patented to us, although the novel features hereof might be applicable in other types of machine.

The principal object hereof is to perfect the construction and operation of button 25 attaching machines for rendering them more efficient, more certain in operation and more simple to handle and adjust.

Other and more particular objects will be developed in the hereinafter following 30 description of an illustrative machine embodying the improvements.

To the attainment of the objects referred to, this invention consists in the novel combinations, arrangements, devices, mechanisms, details and other features shown or 35 described herein.

In the accompanying drawings forming a part hereof, Figure 1 is a front elevation of a button attaching machine embodying 40 the present invention, the same being partly broken away and sectioned to show certain interior parts. Fig. 2 is a left-hand elevation of certain details, including work support and apron therefor. Fig. 3 is a front 45 elevation of the button reservoir and chute and connected parts. Fig. 4 is a right-hand elevation of the parts shown in Fig. 3, assuming same to be tipped upright. Fig. 5 is a left-hand elevation, on an enlarged 50 scale, of the parts located directly at the sewing point. Fig. 6 is a section on the plane 6-6 of Fig. 3. Fig. 7 is a rear ele-

vation of the parts at the lower end of the chute. This view is a reverse view to that of Fig. 3 and the extension 140 is shown 55 broken off short of the set screw. Fig. 8 is a plan view of the button reservoir with the cover removed. Fig. 9 is a section on the plane 9-9 of Fig. 8. Fig. 10 is a section on the plane 10-10 of Fig. 9. Fig. 60 11 is a perspective view of the button agitating member in the reservoir.

Similar reference numerals designate corresponding parts in the several views.

The work W may be considered as a portion 65 of a shoe to which a series of buttons are to be successively attached by thread. The general parts of the machine include a base 20 supporting above it a head 21 extending laterally to form an overhanging 70 arm 22, in which is supported the main shaft 23. Beneath the work is a work-support 75 24 which may be movably held in a housing or bracket 25 and actuated by suitable mechanism from a cam 26 on the main 80 shaft, the work-support lowering slightly during feeding of the work and lifting during needle operations to clamp the work. Beneath the work also is a thread wheel 29, shown located on the bracket 25; also a 85 looper 30 suitably supported and actuated from a cam 31 on the main shaft.

The details of the thread mechanism and the coöperation thereof with the feeding and button supplying devices need not be 90 fully described as they are generally well-known. The preferred operation, however, of the machine will now be set forth. The operation may be as set forth in prior Patent No. 1,063,885 and other analogous prior 95 patents. A button having been fed to a point above the work and beneath the needle with the shank eye of the button positioned horizontally, the hooked needle makes its first descent through the button's eye and through the work to where the thread, supplied from below, is fed to the needle, which thereupon ascends drawing a primary thread loop through the button's eye. Thereupon the needle descends a second 100 time, through the primary loop but outside the button's eye, either the needle or the work and button having been slightly displaced in the meantime. The needle, pene-

frating the work a second time, is supplied with a secondary thread loop below the work, and, on ascending, the needle draws the secondary loop through the primary 5 loop and tightens the latter. When the needle is at its upper position the spreader comes into play to engage the secondary loop, which the needle thereupon disengages, for example, by a slight relative movement 10 toward and from the spreader, permitting the latter to place the thread loop over the head of the button, the spreader tipping down and shedding the loop, which is then tightened by suitable take-up devices, so 15 that the two loops and button shank, now interlocked, are securely drawn to the fabric and the loops formed into a knot. There- 20 after, the work being fed forward the required distance, the succeeding button is similarly treated with the same thread, so that eventually the entire series of buttons 25 is properly secured by stitching to the work.

One feature of improvement shown herein is an apron 32 slightly below and forward 25 of the work-support, it consisting of a hollow box-like structure adapted to be moved out of and into position, so as to permit access to the thread wheel 29 and other working parts while protecting the work 30 from being injured or soiled by the working parts. A convenient way of movably mounting the apron 32 is by means of a spring hinge 33, Fig. 1, permitting the apron to be swung to the right, its open 35 position shown in dotted lines in Fig. 2.

The work may be fed between operations in any suitable manner, for example, by a feed prong 34 constructed and operated in a well-known manner.

40 The illustrated parts below the work have now been fully referred to.

The main shaft at its right end is surrounded by a loose belt pulley 40, which may at will be coupled to or uncoupled from 45 the shaft by a suitable clutch device located at 41.

The needle 44 may, as usual, be of the hooked straight form and secured at the lower end of a reciprocating needle bar 45 50 operated in a usual way from a cam 46 on the main shaft.

A presser-foot 49 may be employed which is relatively fixed, the work-support moving from and toward it. The presser-foot is 55 formed in two halves, which may, as usual, be adjustable toward and from each other and adjustable in height. An improved feature shown is the contour of the opposed halves of the presser-foot such that each 60 button standing therebetween is upheld in a vertical position, so as to insure the proper spreading of the secondary thread loop over the button. By so constructing the presser- 65 foot, movable devices to uphold the button are dispensed with.

Coöperating with the needle is shown a cast-off 51, which may be of usual type and supported on a cast-off bar 52 which receives its proper up-and-down movements in a usual way through coöperating lugs on the 70 needle bar and cast-off bar respectively, aided by a spring retaining device 53. Also coöperating with the needle and other described parts may be employed the usual spreader 55, which swings in to take the secondary loop from the hooked needle, spread the loop open and then tips to shed the loop over the button. An arm on the spreader 75 may be contacted by a movable device 56 for tipping the spreader against the resistance of a spring 57 in a manner already known and not claimed *per se* herein.

Another improved feature shown herein is a novel form of needle backing device 60, more particularly shown in Fig. 5. This is 80 purely self-acting, needing no attention nor any cam operation. It is shown pivoted at 61 between the two halves of the bifurcated presser-foot and having a rear stop arm 62 engaging a stop pin 63 when in normal position, as shown in full lines. A coiled spring 64, having one end fastened to a fixed place and the other end to the backer 60, serves to press the latter with sufficient force to hold it normally securely in the position shown. The needle backer itself is in the form of an arm which, when in normal position, extends in a direction substantially at right angles to the needle, the extremity of the backer being of suitable 90 needle engaging form and contacting directly behind the needle. The particular importance of this feature is the protection of the needle against deflection or continually repeated deflections as a bending tendency is applied to the needle. While a needle will resist displacement and will restore itself to normal position upon a small deflection, it is found that deflections repeated many times eventually cause a permanent strain, so that the needle slightly loses its shape, and this may, by improper co-operation with other parts, bring about irregular or unsatisfactory button attaching results or even conflict and breakage of 100 parts.

Particularly it is true that the spreader 55, when swinging rearwardly to enter the secondary thread on a needle, causes a serious stress. The spreader not only tightens 105 the loop by tending to spread it, but actually moves rearward, so that there is a decided tendency to bend the needle to the rear during the attachment of each button.

The backer 60 effectively protects the 110 needle against permanent bending or injury in this respect. Moreover, the backer automatically places itself in operative position for the purpose and yet is able to yield at suitable times, so as not to interfere with the 115

proper operation of the needle. Thus, on each descent of the needle, the needle bar 45, which otherwise might conflict with the needle backer, is able, owing to the yielding nature of the latter, to swing it downward to the dotted position shown in Fig. 5.

The button supplying means includes a suitable elevated button reservoir, a button chute leading therefrom to the sewing position, agitating means within the reservoir for causing buttons to enter the chute and button clamp means at the lower extremity of the chute for holding each successive button in proper attaching position relatively to the work and needle.

The general arrangement of the reservoir 70 and the chute 100 may be as indicated in said prior Patent 1,063,885, the chute being movable relatively to the reservoir and the latter being adapted to be swung over about a pivot 72 for dumping out the buttons.

The reservoir 70 has a cover 71 openable for inserting and removing buttons which are supposed to be supplied in bulk and fed singly in orderly position to the passages leading from the reservoir to the chute. Fig. 1 shows the position of the reservoir and the oscillating agitator shaft 73, which operates the devices within the reservoir. The agitator shaft connections will be later described. The further details of the reservoir are better shown in Figs. 4, 8, 9, 10, and 11.

Fig. 3 shows that the reservoir is bodily tipped so as to incline downward at the right, tending to carry the buttons by gravity to the lower right-hand corner. Instead of having a simple cup shape, the reservoir is preferably constructed with a wall 75, which is curved both horizontally and vertically, as indicated by the top view, Fig. 8, and also the left-hand elevation, partly in section, of Fig. 9. By this arrangement gravity tends always to bring the buttons to the general position indicated at 76 in front of the oscillating agitator device.

The agitator device hereof comprises several elements, all carried by the agitator shaft 73. Extending downward from the shaft 73 is an arm 77, having an arc shaped button lifter 78 at its extremity, and a button pusher 79 in the form of a curved plate extending laterally, as best shown in perspective in Fig. 11. The shaft also actuates a forwardly extending member 80, which on each downward stroke tends to strike or force down any buttons which have been lifted too far or failed to enter the outlet passage.

The button lifter 78 and the arm 77 carrying it extend between the right-hand wall of the reservoir and the interior curved wall 75, the lifter 78 moving from the curved wall into the interior of the reservoir at its lowest portion, so as to force a number of

buttons upward at each oscillation, whereby one or more buttons will usually take a suitable posture to fall within the button exit shown at 81.

The member 80, which moves downwardly for dislodging accumulated buttons and assisting the entry of buttons into the exit passage, may consist of a tightly coiled spring screwed or otherwise secured upon a pin projecting from a supporting member 82 secured to the agitator shaft 73. The introduction of the spring 80 is of considerable importance in not only increasing the durability of the device but in preventing breakage, which might occur with a rigid member employed to kick the buttons downwardly. The use of the spring itself for kicking the buttons gives a light touch or blow and avoids injury to the buttons themselves.

The button pushing plate 79 extends beneath the curved plate 75 or between that and the bottom of the reservoir. Fig. 8 shows the curved pushing plate in retracted position. Its purpose is to cause the remaining buttons, when the reservoir is almost empty, to be fed forward and downward into a position in front of the lifter so that the latter may properly act upon the buttons, as described.

By means of the described agitator including the three coöperating portions, it is found that not only is great durability and ease of action secured, but efficiency and ability to cause all the buttons supplied to the reservoir, including the very last button, to be fed to the exit passages and thereby to the chute which leads to the attaching position.

The exit passages of the reservoir are shown in dotted lines, Fig. 9, as leading downward, and, as seen in Fig. 6, they are in register with the passages in the chute 100, so that the fed buttons are properly passed from reservoir to chute.

The agitator shaft portion 73 is shown connected by a disconnectible spring clutch device 85 with a second shaft portion 86 in alignment therewith. The details and operation of the clutch device are explained in said prior Patent 1,063,885. The shaft portion 86 inclines downwardly toward the driving end of the main shaft and at its extremity is provided with a swinging arm 87 connected by a link 88 with a vertical arm 89 at the rear of the machine, the latter pivoted to a fixed standard 90 at its lower end and having at an intermediate point a stud 91 engaging in the groove of a cam 92 attached to or formed in one part with the belt pulley 40. By this arrangement the parts 89, 87, 86, 73, 78, 79, and 80 are continuously oscillated whether or not buttons are being attached, so that, when the attaching mechanism stands idle, the button feed-

ing means is operating to supply the chute with an extended series of buttons ready for subsequent operations.

The chute 100 may consist of two parts 5 between which the button heads pass and one or both of the parts being kerfed to guide the button shank. The left-hand chute part 101 and the right-hand chute part 102 are shown in cross-section in Fig. 10 with the button 13 between them, while in Figs. 1 and 3 the chute section 101 is shown journaled by a horizontal pivot shaft 103 to permit the lower end of the chute to swing 15 forwardly and rearwardly from and toward the button attaching position. The space between the two chute sections may be adjustable by relatively separating the sections or adjusting them toward each other. As 20 shown, the section 102 is adapted to be adjusted from and toward the section 101. The outlet passage of the reservoir is shown as formed between the gate of the reservoir and the right-hand end plate 105, which engages with a device 106 carried by the movable chute section 102, so that, under the 25 influence of spring 107, the plate 105 partakes of the adjustment of the chute. By these adjusting devices buttons having various sized heads may be accommodated.

30 Referring now more particularly to the means of adjusting the chute opening, the same is best illustrated in Figs. 3 and 4. A novel feature of improvement is the employment of a pair of coöperative adjusting devices located at removed points on the length 35 of the chute and actuated in unison to cause the chute sections at both ends and at all parts to simultaneously approach or recede, thereby insuring accurate and uniform adjustment. For this purpose it is preferred 40 to employ a pair of screw devices 110, 111, each of them rotatively fitted in the chute section 102 and each having screw-threaded connections, as shown, with the chute section 101. By now turning the screw devices 45 110, 111, equal amounts the chute sections at all points and the reservoir plate 105 will equally and uniformly adjust for different sized button heads. This result is herein 50 shown as accomplished by means of a connecting link 112 extending from a disk or wheel on the screw device 110 or wheel 113 to the arm 114 on the screw 111. The disk 113 on the upper screw may take the form of a 55 knurled wheel or head, as shown, to facilitate manual adjustment of the parts. By now turning the head 113, the link 112 is moved up or down and the two screws 110, 111, are equally rotated. Each screw has 60 a high pitch, so that a partial revolution will give the maximum amount of throw desired for any chute adjustment.

The adjusting devices may be calibrated as by means of a scale shown at 115, so as 65 to predetermine various chute widths, and

a locking device may be employed in the form of a screw 116 engaging a circular slot in the disk 113, the screw being loosened to permit adjustment and tightened to lock the parts.

Another illustrated feature of improvement herein is the combination with the chute of means for normally restraining the buttons from passing out at the lower end and means whereby the passage may be 70 opened to permit the buttons to freely run out for the purpose of emptying the chute when desired. Normally the buttons are restrained by a yielding stop 130, herein-after to be more fully described. In order to 75 permit the free exit of the buttons when desired, it is preferred to provide a movable chute portion 119, preferably a part of the right-hand chute section 102, which is at the lower side of the incline chute. The 80 portion or block 119 may, for example, be fitted to swing about a pivot 121, it having a stop screw 120 for insuring its accurate position when closed. Fig. 3 shows in full lines the normal position of the parts, and 85 in dotted lines the block or gate is shown open at 119°. When the chute is thus 90 opened, the buttons in the chute freely run out, thus permitting inspection, repair and adjustment or the replacement of the buttons by buttons of a different character. When the gate is closed, it fits solidly into 95 position, restoring the continuity of the chute passage, and is there firmly held by a locking device 122. The device 122 swings 100 about a pivot 123 at right angles to the pivot 121. For convenience, the pivot 123 may be concentric with the pivot of the arm 114, before referred to. The device 122 has a finger piece 124 by which it can be moved 105 between its operative position shown in Fig. 3, and in full lines in Fig. 4, or its inoperative position, shown in dotted lines in Fig. 4. The finger piece 124 has a projection 125 which lies against the front surface 110 of the block 119, as seen in Fig. 3, when the parts are locked in normal position. The operator, by pulling the finger piece 124 forwardly, releases the gate or block 119, which 115 may then be swung out from the chute for the purpose specified. The device 122 is of a spring character so as to give it frictional pressure against the gate 119 when the parts are locked.

The stop device 130, at the extremity of 120 the chute, is of an improved construction. It is adapted to stand in the path of the shanks of the buttons. The buttons descend in succession and the shanks, as usual, project horizontally through the left-hand 125 opening in the chute portion 101. The yielding stop 130 is so positioned as to contact the button shanks and thereby position them directly beneath the needle 44. The button shank stop 130 is shown in the form 130

of a swinging plate pivoted at 131 and having an extension 132 to which a convenient form of spring 133 is attached, so as to hold the stop 130 in the position shown in Fig. 5, 5 yet to permit its yielding as the foremost button and the chute relatively separate. As the work feeds toward the rear or as the chute retracts toward the front, the button passes out of the chute, this action taking 10 place between the formation of the primary thread loop and the final spreading of the secondary loop over the head of the button, which at that time must be free.

Coming now to the yielding stop 130 for 15 the shanks of the buttons, that is best shown in Figs. 5 and 7 as consisting of a light metallic plate pivoted at 131 and having an extension 132, acted on by a spring 133 to hold the stop normally in the position indicated. 20 The buttons, descending toward the extremity of the chute, have their shanks outstanding horizontally from the slot, seen in Fig. 5, and the shank of the foremost button comes into contact with the stop 130, 25 which accurately positions it beneath the needle 44, so that, when the button is clamped, it is so held that there can be no conflict in operation or breakage of parts. On the other hand, the stop 130 readily 30 yields to permit the button to pass out of the chute at the proper time.

In addition to the button shank stop 130 is shown a yielding button head stop 135 associated with the button head clamp 136, 25 arranged and operated in a manner generally similar to the stop and clamp in said prior Patent 1,063,885. In the present machine the button head clamp 136 is made of increased horizontal dimension or width, so 40 that it not merely clamps the button being attached, but acts upon the head of the succeeding button to force it slightly back, preventing interference. The clamp 136 swings upon a pivot stud 137 projecting 45 from the chute section 102, while the stop 135 swings on a stud 138 carried on the clamp 136. A spring 139 holds the stop 135 yieldingly in a position slightly outstanding 50 with respect to the clamp 136, as seen in Fig. 7, where the stop is in full lines and the clamp is shown in dotted lines behind it.

The clamp 136 has an operating extension 140, a spring 141 serving to normally hold it lightly in retracted position, so that the 55 buttons may descend freely to lowermost position. At the extremity of the extension 140 is a set screw 142 upon which bears an operating spring arm 143, which extends upwardly and to the right to where at its extremity it has an off-set 144 contacted by a cam lever 145 actuated from the main shaft by a cam 146, a spring 147 holding the cam lever in retracted position. By this construction the main shaft controls the cam 60 lever and, through it, the forward swinging 65

of the clamp 136 so as to lock or clamp the foremost button in attaching position before the descent of the needle to form the primary loop.

As usual, the chute has an extension 150, 70 Fig. 4, to the rear whereby it may be swung forwardly and rearwardly in harmony with the other operations of the machine, and this extension 150 may be suitably connected with a crank shaft 151 (see Fig. 1) whereby 75 the main shaft controls the oscillation of the chute.

It will thus be seen that there has been described a button attaching machine embodying the improvements and attaining the 80 objects and advantages above recited, and other advantages therein will be apparent to those skilled in the art.

Since many matters of design, arrangement, detail and other features may be variously altered without departing from the invention, no limitation to such features is intended excepting so far as specified in the 85 appended claims.

What is claimed is:

1. A button attaching machine including in combination, attaching means, a button reservoir, a chute between said reservoir and said attaching means, the said reservoir shaped to bring buttons by gravity to a button lifting point therein and having an outlet to said chute located above said lifting point, and a reciprocating rigid plate-like button lifter movable in said reservoir between said lifting point and said outlet, said 95 lifter adapted in its retracting movement to withdraw substantially out of the button containing portion of the reservoir.

2. A button attaching machine including in combination, attaching means, a button reservoir, a chute between said reservoir and said attaching means, the said reservoir shaped to bring buttons by gravity to a button lifting point therein and having an outlet to said chute located above said lifting point, and a reciprocating rigid plate-like button lifter movable in said reservoir between said lifting point and said outlet, a button striking member movable above said outlet for moving buttons downward, and means for moving said lifter and member in harmony, said lifter adapted in its retracting movement to withdraw substantially out of the button containing portion of the reservoir.

3. A button attaching machine including in combination, attaching means, a button reservoir, a chute between said reservoir and said attaching means, the said reservoir shaped to bring buttons by gravity to a button lifting point therein and having an outlet to said chute located above said lifting point, and a button lifter movable in said reservoir between said lifting point and said outlet, a rigid plate-like button pusher 100

adapted in each reciprocation to withdraw from and enter into the button containing portion of the reservoir for assisting the last few buttons to pass to said lifting point 5 to be acted upon by said lifter, and means for reciprocating said lifter and said pusher.

4. A button attaching machine including in combination, attaching means, a button reservoir, a chute between said reservoir and 10 said attaching means, said reservoir shaped to bring buttons by gravity to a button lifting point therein and having an outlet to said chute located above said lifting point, an elongated reciprocating plate-like button 15 lifting member movable in said reservoir between said lifting point and the outlet and a supplemental button pushing plate having an inclined edge adapted to pass from and into the button containing portion 20 of the reservoir for assisting the last few buttons to pass to said lifting member.

5. A button attaching machine including in combination, attaching means, a button reservoir, a chute between said reservoir 15 and said attaching means, the said reservoir shaped to bring buttons by gravity to a button lifting point therein and having an outlet to said chute located above said lifting point, a rigid button lifter movable in said 30 reservoir between said lifting point and said outlet, a reciprocating elongated plate-like button pusher for assisting the last few buttons to pass to said lifting point, a button striking member movable above said outlet 35 for moving buttons downward, and means for actuating said lifter and said pusher and said member in coöperation.

6. A button attaching machine including in combination, attaching means, a button 40 reservoir, a chute between said reservoir and said attaching means, an agitator shaft extending to said reservoir, an arm projecting from the shaft, a rigid plate-like button lifter carried by the arm, a button pusher 45 carried by the arm, said pusher consisting of a plate adapted to move from and into the button containing portion of the reservoir, a button striking member arranged to be actuated by said shaft, and means to oscillate 50 said shaft for causing the actuation of the lifter, pusher and striking member.

7. A button attaching machine including in combination, attaching means, a button reservoir, and a button chute between said 55 reservoir and attaching means, said chute comprising two sections between which the button heads pass, a plurality of movable devices each adjustably connecting said sections, and a single means for actuating both 60 said devices in unison to alter the space between the sections.

8. A button attaching machine including in combination, attaching means, a button reservoir, and a button chute between said 65 reservoir and attaching means, said chute

comprising two sections between which the button heads pass, a plurality of screws each adjustably connecting said sections, and a single means for turning both said screws in unison to alter the space between the sections. 70

9. A button attaching machine including in combination, attaching means, a button reservoir, and a button chute between said reservoir and attaching means, said chute 75 comprising two sections between which the button heads pass, a plurality of high-pitched screws each adjustably connecting said sections, and a single means for turning both said screws in unison to alter the space 80 between the sections, comprising an offset member at the head of each screw, and a link connecting said offset members.

10. A button attaching machine including in combination, attaching means, a button 85 reservoir, and a button chute between said reservoir and attaching means, said chute comprising two sections between which the button heads pass, a plurality of movable devices each adjustably connecting said sections, and a single means for actuating both 90 said devices in unison to alter the space between the sections, and means to lock the parts in any adjusted position.

11. A button attaching machine including 95 in combination, attaching means, a button reservoir, and a button chute between said reservoir and attaching means, said chute comprising two sections between which the button heads pass, a plurality of high- 100 pitched screws each adjustably connecting said sections, and a single means for turning both said screws in unison to alter the space between the sections, comprising an offset member at the head of each screw, and a link 105 connecting said offset members, and a concentric locking device for securing one of the screw heads in adjusted position.

12. A button attaching machine including 110 in combination, attaching means, a button reservoir, and a button chute between said reservoir and attaching means, said chute being inclined and having opposed sections, one under the other, said under section having the bottom portion thereof adapted to 115 be swung out and in to open or close the chute at will.

13. A button attaching machine including 120 in combination, attaching means, a button reservoir, and a button chute between said reservoir and attaching means, said chute being inclined and having opposed sections, one under the other, said under section having the bottom portion thereof adapted to be swung out and in to open or close the 125 chute at will, and means to normally maintain the chute portion locked in closed position.

14. A button attaching machine including 130 in combination, attaching means, a button

reservoir, and a button chute between said reservoir and attaching means, said chute being inclined and having opposed sections, one under the other, said under section having the bottom portion thereof adapted to be swung out and in to open or close the chute at will, and means to normally maintain the chute portion locked in closed position comprising a manual lock device swingable in a plane at an angle to the plane of swinging of the chute portion.

15. A button attaching machine for shank eye buttons including in combination, attaching means, a button chute for conducting buttons to attaching position with the shanks outstanding to be engaged by the attaching means, and a pivoted button-shank stop carried by the chute and adapted to be contacted by the button shank for yieldingly 20 stopping each button shank in proper attaching position.

16. A button attaching machine for shank eye buttons including in combination, attaching means, a button chute for conducting buttons to attaching position with the shanks outstanding to be engaged by the attaching means, and a pivoted button-shank stop carried by the chute for yieldingly 25 stopping each button shank in proper attaching position; means to stop the button head in normal position, and a spring 30

to yieldingly hold the button in such position.

17. A button attaching machine for shank eye buttons including in combination, attaching means, a button chute for conducting buttons to attaching position with the shanks outstanding to be engaged by the attaching means, a button head clamp adapted to be moved toward the foremost 40 button after the button has reached attaching position and to clamp the foremost button in attaching position in the chute and to simultaneously move the succeeding button away from the first button.

45 18. A button attaching machine for shank eye buttons including in combination, attaching means, a button chute for conducting buttons to attaching position with the shanks outstanding to be engaged by the attaching means, a button head clamp adapted to clamp the foremost button in attaching position in the chute, a cam operated spring-arm for operating the clamp, and an adjusting screw between clamp and arm.

50 In testimony whereof we affix our signatures in presence of two witnesses.

JOHN KIEWICZ.

CHRISTIAN H. T. HAGELSTEIN.
